C. R. NORMANDY,
SUSPENSION HOOK,
APPLICATION FILED DEC. 7, 1916.

1,285,336.

Patented Nov. 19, 1918.

UNITED STATES PATENT OFFICE.

CHARLES R. NORMANDY, OF WASHINGTON, DISTRICT OF COLUMBIA, ASSIGNOR TO STANDARD MOTH BAG COMPANY, OF WASHINGTON, DISTRICT OF COLUMBIA, A CORPORATION OF VIRGINIA.

SUSPENSION-HOOK.

1,285,336.

Specification of Letters Patent. Patented Nov. 19, 1918.

Application filed December 7, 1916. Serial No. 135,671.

To all whom it may concern:

Be it known that I, CHARLES R. NORMANDY, a citizen of the United States, residing at Washington, in the District of Columbia, have invented certain new and useful Improvements in Suspension-Hooks, of which the following is a specification.

The primary object of my invention is to provide a hanger or garment closure of the type shown in United States Letters Patent 1082858.

A further object of my invention is to provide a hanger which is adapted to suspend a closure or receptacle from a wall or from a shelf.

A further object of my invention is to provide a hanger having two suspending points and common pivot points.

A further object of my invention is to provide a two point suspension hanger wherein one point of suspension is brought in the operative position when the other point of suspension is placed in inoperative position.

A further object of my invention is to provide a suspension hanger comprising two arms disposed at an angle to each other and provided with a point of suspension, at the juncture of the two arms, and a point of suspension, at the end of one of said arms, said points of suspension being in different vertical planes; and with these and other objects in view my invention consists of the parts and combinations of parts hereinafter specified.

In the drawings Figure 1 is a perspective view of a closure with my improved hanger attached thereto, said hanger being positioned for wall suspension.

Fig. 2 is a perspective of a closure with my improved hanger attached thereto, hanger being shown at an angle of 90 degrees from that shown in Fig. 1.

Fig. 3 is a vertical sectional view through the closure and the center point of suspension with the hanger in the position shown in Fig. 2.

The reference numeral 1 designates a closure which may be of any desired construction and adapted to serve as a protection for clothing, etc.

Closures of this character have been usu-

ally supplied with a suspending means positioned in the center thereof, and it has been found, that where it is desired to suspend the closure from the wall or any other vertical support, that the suspending of the closure from the central point to a wall has a tendency to place an unevenly distributed strain upon the closure which results in the distortion of the closure.

By my invention I provide, in one attachment, two suspension points, one for wall suspension and the other for shelf or other over-head suspension. This attachment consists of two arms 2 and 3 which are disposed at an angle to each other and may be formed from a single piece of wire of suitable gage, there being a suspending eye 4 at the juncture of the arms 2 and 3, 70 said eye being formed from the same piece of wire as the arms 2 and 3, and being substantially in the plane of the arm 2 to serve as a wall suspension. The arm 3 terminates in the suspending eye 5 disposed at 75 substantially a right angle to the eye 4, the body of the eye 5 being disposed to one side of the arm 3 as clearly shown in the drawings. The arm 2 at its lower end is rebent to form a closed hook 6, which is adapted 80 to be secured to an eye bolt or similar device 7 which is secured by means of the nut 8, to the top 10 of the closure 1, said eye bolt being secured to or having co-operative connection with the suspending eye 5, positioned and in line with the arm 3, whereby the body of the eye 5 is disposed to one side of the pivot point 7, whereby the hanger may rock on the pivots 7 and 11 to the position shown in Figs. 2 and 3 and present suspending eye 5 in the vertical position for shelf or other over-head suspension. The arm 2 terminates at its lower end in a closed hook 6, which is adapted to engage the eye bolt 11, which eye bolt is secured to the top 95 10 in the same manner as is the eye bolt 7, above described.

From the above it will be seen that when the suspending hook is employed to suspend the closure from a nail 12 against a wall or other vertical support the suspending hook assumes the vertical position shown in Fig. 1, with the suspending eye 5 flat upon the top of the closure. When it is desired to

suspend the closure from a shelf or other over-head support the suspension hook or device is permitted to drop to the position shown in Figs. 2 and 3 whereby the suspension eye 5 is presented in a vertical position as shown in Figs. 2 and 3, the arms 2 and 3 and the eye 4 being folded down on the top of the closure. The fact that the body of the eye 5 is disposed to one side of the eye bolt 7 enables me to provide a two point suspension hook which may be folded flat upon the top of the closure. When a suspending hook of this character is employed in connection with collapsible moth proof bags and wardrobes it is desirable to have the suspending means folded down upon the top of the closure to economize space and reduce the size of the package for shipment.

While I have, for the purposes of illustration, shown my two point hanger made of a single piece of wire, it is of course obvious that many changes may be made in the details of construction within the scope of the claims.

25 What I claim is:

1. A suspension hook, comprising two arms disposed at an angle to each other, a vertically disposed eye at the juncture of

said arms and substantially in the plane of one of said arms, an eye at the end of and 30 disposed to one side of the other arm and at an angle to the other eye and means for securing said hook to an article.

2. A suspension hook, comprising two arms disposed at an angle to each other, a 35 vertically disposed eye substantially in the plane of one of said arms, an eye disposed substantially in the plane of the other arm and at an angle to the other eye, a pivot pin secured to the lower end of one of said 40 arms, and a pivot pin secured in the eye of the other of said arms.

3. A suspension hook, comprising two arms disposed substantially in the same plane and at an angle to each other, an eye 45 at the juncture of said arms, an eye at the end and bodily disposed to one side of the other of said arms, said eyes being disposed at an angle to each other, a pivot pin secured to the lower end of one of said arms, and 50 a pivot pin secured within the eye of the other of said arms, but in alinement with the other pivot pin.

In testimony whereof I affix my signature.

CHARLES R. NORMANDY.
